UNITED STATES PATENT OFFICE.

VICTOR H. PALM, OF BUTLER, PENNSYLVANIA.

PUMP VALVE.

Application filed August 6, 1921. Serial No. 490,402.

To all whom it may concern:

Be it known that I, VICTOR H. PALM, a citizen of the United States, and resident of Butler, in the county of Butler and State of Pennsylvania, have invented a new and useful Improvement in Pump Valves; and I do hereby declare the following to be a full, clear, and exact description thereof.

My invention relates to pumps for deep wells for pumping water or oil.

The object of my invention is to provide a pump of this character in which the capacity for delivering the liquid from the lower side of the pump to the upper side is greatly increased over the ordinary pumps now in use for this purpose, while at the same time the liquid keeps the working barrel washed clean, and the chances for sediment cutting the packing rings of the valve are greatly reduced.

A further object of my invention is to provide means whereby the liquid leaking past the valve is used to increase the packing action of the packing rings, all as more fully hereinafter set forth.

In the accompanying drawing, Fig. 1 is a vertical section of a working barrel showing my invention applied thereto with the valve in a position on the upward stroke; Fig. 2 is a like view showing the position of the valve on the downward stroke; Fig. 3 is an enlarged vertical section of a portion of the valve showing the packing rings and cups; Fig. 4 is a plan view of the pump valve stop; Fig. 5 is a plan view of the pump valve; and Figs. 6, 7 and 8 show details of the packing rings.

In the drawing the numeral 2 designates a suitable working-barrel at the lower end of which is arranged the lower or standing valve 3 which is of the ordinary type.

The numeral 4 indicates an ordinary sucker-rod section provided with the threaded socket 5 which engages the screw threaded portion 6 at the upper end of the valve-stem 7. At the lower end of the valve stem 7 is the valve 8.

Connected to the threaded portion 6 of the valve-stem 7 is the stop 9 which is in the form of a spider, as shown in Fig. 4.

Interposed between the valve 8 and the stop 9 is the valve-sleeve 10, said valve-sleeve having the annular grooves 11 formed therein to receive the packing. This packing consists of the leather or like cups 12 which fit down in the undercut portions 13

of the grooves 11, and on the outside of said cups, engaging said grooves, are the metal packing rings 14 which are divided along the lines 15, as indicated in Fig. 7. The cups 12 are reduced in thickness, as at 16, so as to leave the spaces 17, and split spring rings 18 are employed which act to force the cups outwardly, so as to, in turn, force the packing rings 14 outwardly into close engagement to the inner walls of the working-barrel. The spaces 17 also provide for the admission of liquid leaking past the sleeve 10 back of the cups, and the pressure occasioned thereby will act to force the cups 12 outwardly and so force the packing rings 14 outwardly and prevent leakage. The undercut seats 13 for the cups 12 cause the cups to extend across and pack the lower faces of the rings 14, thereby reducing leakage still further, and they also pack the joints 15 in the rings 14 and the joints 15^a between the overlapping ends of the rings.

The valve-stem 7 is provided with the wings 19 which act to centralize the stem, said wings engaging the inner face of the valve-sleeve 10, and the valve-stem 7 is reduced in diameter between the wings 19, as shown at 19^a, so as to compensate for the space taken up by the wings 19.

A metal plug 20 may be inserted in an opening 21 formed in the valve 8, and an opening may be drilled through said plug 20 in case it is desired to leak off part of the liquid, as is common practice when pumping oil wells.

Extending down from the lower end of the valve-stem 7 is the threaded portion 22 which is adapted to be screwed into the threaded seat 23 in the standing-valve 3 or in the drop-valve which often rests on the standing valve 3, according to common practice, so that when it is desired to pull said valve the connection is made with the stem 7, and the standing-valve or drop-valve is lifted at the same time that the upper valve is pulled, thereby creating a saving in time and labor.

When my improved pump is in operation the lowering of the sucker-rod 4 will lower the valve-stem 7 and the stop 9 will engage the valve-sleeve 10 and lower said sleeve, while at the same time the valve 8 is moved away from said sleeve so that the liquid passes up through the sleeve 10 to a point above. On the upward stroke of the pump

the valve 8 is brought up into engagement with the sleeve 10 to shut off the passage of the liquid through said sleeve, and the sleeve then moves with the stem up in the 5 working barrel and in this way the fluid is raised up to the top of the well.

The manner in which the fluid passes through the sleeve 10, due to the large inlet, keeps the barrel washed clean, so that 10 there is little chance for sediment collecting around the sleeve to cut the packing rings, but in case of any wear the fluid leaking past will get into the spaces 17 and so act by pressure to force the cups and packing rings tightly against the inner walls 15 of the working barrel, and so seal the joint.

What I claim is:

1. In a pump, the combination with the working-barrel, of an integral tubular valve-sleeve engaging the walls thereof, a valve 20 adapted to seat against the lower surface of said valve-sleeve, a valve-stem connected to said valve, a centering spider connected to said valve-stem above said valve-sleeve, 25 having a plurality of radial projections forming a stop, and means for reciprocating said valve-stem.

2. In a pump, the combination with the working-barrel, of an integral tubular valve-sleeve engaging the inner walls thereof, a valve-stem, a valve on said valve stem 30 adapted to seat against the lower surface of said valve-sleeve, wings integral with said valve-stem engaging the inner walls of said 35 sleeve, and a centering spider having a plurality of radial arms extending substantially the full diameter of said sleeve and forming a stop for said valve, said spider being carried by said valve-stem above said 40 sleeve.

3. In a pump, the combination with a working-barrel, of a valve-sleeve engaging the inner walls thereof, a valve-stem, a valve 45 on the lower end of said valve-stem adapted to engage the lower end of said valve-sleeve, a stop at the upper end of said stem, said stop being also adapted to center 50 said valve stem in the working barrel and a soft metal plug engaging an opening in said valve and adapted to be pierced to permit leakage of fluid therethrough.

4. In a pump, the combination with a working-barrel, of a valve-sleeve engaging the inner walls thereof, internally closed 55 annular grooves formed in said valve-sleeve, flexible cups in said grooves, said cups being formed to allow for space back of same, and split packing rings of metal in said grooves outside of said cups, a valve-stem, 60 a valve connected to said valve stem adapted to engage the lower end of said sleeve, and a stop at the upper end of said stem above said sleeve.

5. In a pump, the combination with the 65 working-barrel, of a valve-sleeve engaging

the inner walls thereof, internally closed annular grooves formed in said valve-sleeve, flexible packing cups in said grooves shaped to form spaces back of said cups, a spring ring engaging each of said cups from the rear, and split packing rings of metal outside of said cups and in said grooves, a valve-stem, a valve at the lower end of said stem adapted to engage the lower end of said valve-sleeve, and a stop at the upper end of said stem of said sleeve.

6. In a pump, the combination of a valve-sleeve adapted for insertion into the working-barrel of a well, annular grooves formed in said sleeve, the said grooves having undercut inner portions, cups seated in the undercut inner portions of said grooves, and packing rings disposed in said grooves outside of said cups.

7. In a pump, the combination of a valve-sleeve adapted for insertion into the working barrel of a well, annular grooves formed in said sleeve, the said grooves having undercut inner portions, cups seated in the undercut inner portions of said grooves, and split packing rings disposed in said grooves outside of said cups, the said rings having overlapping end portions, and the said cups serving to pack the joints between the said overlapping end portions of said rings and the circular joints between said rings and said sleeve.

8. In a pump, the combination with a working barrel, of a valve-sleeve engaging the inner walls thereof, internally closed 100 annular grooves formed in said valve-sleeve, flexible cups in said grooves, said cups being formed to allow for space between said cups and the rear walls of said grooves, split packing rings in said grooves outside 105 of said cups, annular springs disposed in the spaces behind said cups and tending to force said cups outwardly, a valve stem, a valve connected to said valve stem and adapted to engage the lower end of said sleeve, and a stop carried by said valve stem above said sleeve.

9. A working valve for pumps comprising a tubular integral sleeve adapted to fit slidably within a working barrel, and having a plurality of internally closed annular grooves in its outer surface, split metal rings disposed in said grooves, flexible cups disposed in said grooves behind said rings and shaped to provide spaces behind said cups, and annular springs disposed in said spaces and tending to force said cups and rings outwardly.

In testimony whereof, I the said VICTOR H. PALM have hereunto set my hand.

VICTOR H. PALM.
